UNITED STATES PATENT OFFICE.

MARTIN B. ZIMMERMAN, OF LEWISBURG, PENNSYLVANIA, ASSIGNOR TO COLUMBIA COMPANY, OF LEWISBURG, PENNSYLVANIA, A CORPORATION OF PENNSYLVANIA.

MACHINE FOR INSERTING DIAGONAL STRANDS IN WOVEN-CANE FABRICS.

1,011,701.

Specification of Letters Patent.

Patented Dec. 12, 1911.

Application filed April 21, 1911. Serial No. 622,448.

To all whom it may concern:

Be it known that I, MARTIN B. ZIMMERMAN, a citizen of the United States, and a resident of Lewisburg, in the county of Union and State of Pennsylvania, have invented a new and Improved Machine for Inserting Diagonal Strands in Woven-Cane Fabrics, of which the following is a full, clear, and exact description.

10 The purpose of the invention is to provide exceedingly simple, positive and effective means for depressing the warp strands and raising the weft strands in woven cane fabric for the passage of a needle carrying a diagonal strand, and to accomplish the object by the joint downward movement of a bar carrying guide pins for the fabric and a parallel bar carrying depressing fingers for the warp strands in connection with automatically acting fingers that receive and hold elevated the weft strands.

15 A further purpose of the invention is to provide a machine of the character described which will be light, yet strong and compact throughout its entire construction, and further to provide an effective and reliable machine, necessitating comparatively few parts nearly all of which are readily accessible for inspection or repair.

20 The invention consists in the novel construction and combination of the several parts, as will be hereinafter fully set forth and pointed out in the claims.

Reference is to be had to the accompanying drawings forming a part of this specification, in which similar characters of reference indicate corresponding parts in all the figures.

25 Figure 1 is a side elevation of the improved machine; Fig. 2 is a plan view thereof; Fig. 3 is a longitudinal vertical section taken practically on the line 3—3 of Fig. 2; Fig. 4 is a transverse section taken substantially on the line 4—4 of Fig. 1; Fig. 5 is a transverse section taken practically on the line 5—5 of Fig. 1; Fig. 6 is a detail view of the stop employed in connection with the operating mechanism for the elevating fingers for the weft strands; Fig. 7 is a longitudinal section through a portion of the pin-carrying bar and cane fabric, showing the warp strands depressed and the weft strands elevated; and Fig. 8 is a plan view of a piece of cane fabric, illustrating a few 30 of the diagonal strands applied.

The base 10 may be of any dimensions, and from the end portion of the base a tubular pillar 11 extends upward. Said pillar supports an end portion of a horizontal bed A, and an end portion of said horizontal bed, or that end which is adapted to support the working portions of the machine, is in the form of a diamond-shaped table, the points whereof extend in direction of the ends of the bed and in direction of the front and back thereof, as best shown in Fig. 2. In fact, an outer point of the table 12 constitutes the working end of the bed, and at the opposite end portion of said bed a longitudinal slot 13 is made. At the extremity of the slotted end of the bed a grooved pulley 14 is mounted to turn horizontally upon the bracket 15 offset in direction of the front of the machine from the said bed, as shown in Figs. 1 and 2. 75

The needle-operating arm 16 is carried up through the slot 13, and the lower end 17 of this arm is widened and is rendered segmental, but at its lower curved surface is provided with teeth 18 as best shown in Fig. 80 1. Said teeth 18 engage with the teeth of a rack 19 formed at the lower end of a standard 20 which supports the slotted portion of the said bed A. The needle-operating arm 16 is guided in its movement and a pin 21, 85 is secured to the said needle arm 16 and engages with the under face of the bed A. The crank arm 22 extends up from the said operating arm 16 and is pivotally connected to the outer end of a needle B, which needle 90 is supported at its opposite or outer end in a manner to be hereinafter described, and the eye b of said needle is formed at said outer end, as is shown in Fig. 3. A second horizontal peripherally grooved pulley 23 is 95 supported at the outer end point of the table 12 by means of a bracket 24 attached to the table; and said pulley 23 is secured to a shaft 25, which extends down through the arm 24 and through a bracket 26 located 100 below the said table 12, as is shown in Figs. 1 and 3, and said shaft 25 is provided with an attached pinion 27.

A sliding rack C is mounted for movement at the forward inclined portion of the table 12, said rack having movement to and from the pinion 27, which pinion is engaged by teeth 27^a formed on the rack, said sliding rack at its inner end being provided with a handle 28. The rack is 110

preferably L-shaped in cross section, and the teeth 27^a are in its horizontal member; its vertical member is provided with longitudinal slots 29 which loosely receive bolts 30 or their equivalents, that extend into the said table, thus guiding the said slide. The movement of the said sliding rack C controls the movement of the needle B, and this is accomplished by means of an endless belt 31 that passes around the pulleys 14 and 23, and is attached in any suitable or approved manner at one of its stretches to the upper end of the needle-operating arm 16 as is best shown in Fig. 1.

15 A slot 33 is produced in the lower portion of the pillar 11, and through this slot a foot treadle or lever 33^a is passed, being fulcrumed at the rear of the said pillar and extending beyond its front. Said lever occupies a diagonal position relatively to the front portion of the base, so that the operator will have ready control of the sliding rack C. Within said pillar this lever is connected by means of links 34 with a beam 35, which beam extends out through slots 36 in direction of the ends of the machine, and said beam 35 occupies a position at an angle to the treadle 33^a and at a slight angle to the bed A. The beam 35 is held in an upper position by means of springs 37 attached to the pillar 11 and having upward bearing at the end portions of the beam as is shown in Figs. 1 and 3.

35 A bed plate 38 is located over the central portion of the table 12, extending in direction of the ends of the machine, and said bed plate is spaced apart from the table 12 by means of a supporting bar 39, which is more or less diagonally located relative to the said bed plate and is longer than the bed plate, extending beyond its ends. In fact, the supporting plate 39 extends practically from one corner of the bed plate 38 to the opposing diagonal corner. The said supporting plate 39 has its upper end portions recessed or cut away as shown at 40 in Fig. 3. At opposite sides of the supporting plate 39, at its ends, two sockets 41 are formed, which sockets are secured also at their upper ends to opposite diagonal corners of the bed plate 38 as is best shown in Fig. 2.

45 A guide plate D is located above the bed plate 38, and is spaced apart therefrom, the said guide plate D being preferably transversely arched, its upper face being its convexed face, and the weft cane fabric H is made to rest upon this guide plate D while the diagonal strand H' is being passed through the said fabric by means of said needle B. The guide plate D is provided with a series of upwardly-extending pins 42. Said pins are in two rows and are staggered in their general arrangement, the pins of one

50 row being opposite the center of the spaces between the pins of the opposing row as is indicated in Figs. 4, 5 and 7. The needle B in operation passes over said guide plate D, which likewise may be termed a pin plate, passing between the rows of pins and 70 through a suitable guide b' located at the inner end of the said guide plate as is illustrated in Fig. 3. The guide plate D is further provided with a series of transverse centrally located slots 43, and said slots are 75 so located that they are between two diagonally opposing pins 42 on said guide plate D as is best shown in Fig. 7, so that a pin of one row and a diagonally opposite pin of the opposing row will be located between 80 each two slots. The pins 42 are adapted to pass up through the meshes in the woven cane prior to a diagonal strand being woven therein. The said guide plate D is held 85 yieldingly spaced apart from the bed plate 38 by means of downwardly-extending bolts 44, two of which are usually located adjacent to each end of the said guide plate, and said bolts are loosely passed through suitable openings in the bed plate 38, and are 90 provided with nuts 46 at their ends, so as to limit the upward movement of the said guide plate. Springs 45 are coiled around said bolts 44 between the two plates 38 and D, the spring serving to return the guide 95 plate D to its normal position after having been relieved from pressure.

A depressing plate or bar E is located above the guide plate D; and said depressing plate E is provided with a series of 100 downwardly-extending fingers 48 arranged to enter the spaces between diagonally opposing pins 42 to press and hold down the warp strands of the fabric when the depressing bar is carried downward taking 105 with it the guide bar D. In order that the fingers 48 shall not slip during such operation a recess 49 is made in the bottom of each finger 48, capable of receiving a strand of the fabric. As the depressing plate E is 110 forced downward to depress the warp strands, retaining hooks F extend upward and rearward through the slots 43 in the guide plate D, which hooks receive and hold elevated or raised the weft strands adjacent 115 to the pins 42, as is shown best in Fig. 7; and at such time the needle B in passing between the rows of pins 42 will pass likewise between the depressed warp and the elevated weft strands, and thus weave the diagonal 120 strand carried by the needle through the body of the fabric as is shown in Fig. 8, wherein the fabric is designated as H and the diagonal strands as H'. These retaining hooks F are pivoted upon two brackets 125 50 rigidly secured to the body plate 38 as is shown in Fig. 3, and each retaining hook F is provided with a reduced foot section just below its pivot, and said foot sections 51 enter recesses in the upper edges of curved 128

cradle bars 52, the upper edges of which bars are more or less concaved, as is shown in Fig. 5, for one bar. These cradle bars 52 are held properly spaced and have concerted 5 action by front and rear tie rods 53 and 54, and springs 55 secured to the table 12, or the supporting bar 39 at its rear, are carried up over the bed plate 38 to an engagement with the under surfaces of the said tie bars 53 and 54 for the purpose of keeping the 10 cradle bars up to their work with reference to the hooks F. The normal position of the retaining hooks F is that shown in Figs. 4 and 5, wherein it will be observed that 15 they are slightly below the upper face of the guide plate D, which is in its upper or normal position, and that the hooks have an upward and a forward inclination, whereupon by laterally moving the cradle bars 52 in a 20 forward direction the said bars cause the said retaining hooks to assume a vertical position, said position being assumed as the guide plate D is carried downward, thus causing the said hooks to catch and receive 25 the weft strands and hold the same elevated as the fingers 48 on the depressing plate E engage and hold the warp strands depressed. The movement of the cradle bars 52 forward and rearward is automatically accomplished 30 preferably in the following manner: Rearwardly-extending links 56 are secured to the rear tie bar 54, usually at its end portions; and these links 56 are attached to a connecting rod 57, and said connecting rod 35 is pivotally connected with downwardly-extending links 58. Said links in their turn are secured to a crank shaft 59, mounted to turn in suitable bearings 60 supported by the table 12, the crank arm 61 of the shaft 40 59 being given an upward and somewhat of a forward inclination as shown in Fig. 1. The shaft 59, which has a rocking motion, is limited in such motion by producing a curved slot 62 in one of the bearings 60 as 45 shown in Fig. 6, and securing a downwardly-extending crank arm 63 to said shaft 59, the horizontal member of which crank arm has movement in the slot 62. The movement of the crank shaft 59 and the operation of the 50 cradle bars 52 are accomplished by carrying the front or forward end of a lever arm 64 beyond and beneath the front or forward side edge of the bed plate 38 through one of the openings 40 in its supporting plate 39 as 55 is shown in Figs. 1 and 3. This lever arm 64 is preferably given a compound curve, and its rear end is pivoted to a standard 65 carried by the table 12 as best shown in Fig. 4, while a curved link 66 is attached to the 60 lever arm 64 and to the upper end of the crank arm 61, the curvature of said link 66 being in direction of the forward or front side of the machine. The forward or front end of the lever arm 64 is received in a 65 recess 67, produced at one side of the lower

end of a trip finger 69 that is secured to the depressing plate E and extends down at the front or forward side portions of said depressing plate E, the guide plate D and the bed plate 38. The depressing plate E is operated through the medium of the treadle 33^a, and to that end downwardly extending rods 70 are attached to the end portions of said depressing plate E, which rods pass down through the sockets 41 and the table 75 12 to an engagement with the outer end portion of the beam 35.

In the operation of the machine, the parts being in their normal position best shown in Figs. 1, 3, 4 and 5, the cane fabric H is 80 threaded over the pins 42 on the guide plate D and the treadle 33^a is pressed downward, which will carry the beam 35 down, placing its springs 37 under tension, and will also cause the depressing bar or plate E to be 85 drawn downward until its fingers 48 engage with the weft strands of the fabric, whereupon the said plate E is continued downward until the guide plate D is depressed against the tension of its springs 45 far 90 enough to uncover the upper ends of the retaining hooks F, bringing such portions in such relation to the weft strands of the fabric that when the hooks are moved rearward they will engage with said weft strands. 95 Such rearward movement is brought about approximately when the depressing plate E has reached the limit of its downward travel by reason of the operating arm 69 forcing the front end of the lever arm 64 downward, thus pushing forward the connected cradle bars 52, thereby bringing all of the hooks F to an upper position, causing them to receive and hold elevated the weft strands. 100 While the treadle 33^a is yet depressed the slide C is operated past the needle B over the guide plate D between its rows of pins 42 and consequently above the warp strands and below the weft strands as is shown in Fig. 7. An end of the diagonal stand H' is 105 now passed through the eye of the needle B, as is also shown in Fig. 7. The operating mechanism for the needle is now reversed, carrying the needle back to its normal position and causing the attached diagonal 110 strand to be drawn through the path of the needle. When this is accomplished the diagonal strand is caught in any desired manner, and the treadle 33^a is released, whereupon the springs 37 act to force the depressing plate 115 E upward, and the operating arm 69 rocks the front end of the lever arm 64 upward, thus restoring the confining hooks F to their normal position, and at the same time the springs 45 restore the guide plate D to its 120 normal position. The fabric H may now be shifted to receive another diagonal strand, and the operation of the machine is repeated, as described.

It may be here remarked that the shafts 57 130

and 59 belonging to the controlling mechanism for the hook retaining devices F are steadied in their action by means of a spring f, shown in Figs. 2 and 5.

5 Having thus described my invention, I claim as new, and desire to secure by Letters Patent,—

1. In machines for inserting diagonal strands in woven cane fabric, a guide plate 10 for the cane fabric, a depressing device for the warp strands, pivoted elevating devices for the weft strands, and means for simultaneously operating the depressing and elevating devices relatively to the guide plate.

15 2. In machines for inserting diagonal strands in woven cane fabric, a guide plate for the woven fabric, a depressing device for the warp strands, operating to and from the guide plate and also acting upon the guide 20 plate to depress the latter, elevating devices operating through the guide plate when the latter is depressed to elevate the weft strands, and means for operating said depressing and elevating devices.

25 3. In machines for inserting diagonal strands in woven cane fabric, a guide plate for the woven fabric, a depressing device for the warp strands, the said device having depressing action upon the guide plate, elevating devices for the weft strands operating when the guide plate is depressed, a needle adapted to carry a diagonal strand, which needle passes between the two said devices and the strands operated upon thereby, means 30 for operating said needle, and means for simultaneously operating the said two devices relatively to the guide plate, the operating mechanism for the said devices and the operating mechanism for said needle having 40 timed action.

4. In mechanism for inserting diagonal strands in woven cane fabric, a movable spring-supported guide plate for the fabric, a depressing device for the warp strands 45 movable to and from and also adapted for having depressing action upon the guide plate, elevating devices for the weft strands, independent of and operating through the guide plate when the latter is depressed, and 50 means for operating the two said devices.

5. In machines for inserting diagonal strands in woven cane fabric, a movable, spring-supported guide plate for the fabric, a depressing device for the warp strands, 55 movable to and from and also having depressing action upon the guide plate, elevating devices for the weft strands, independent of and operating through the guide plate, pivotal supports for the elevating devices, and means for operating the depressing device and for rocking the elevating devices.

6. In machines for inserting diagonal strands in woven cane fabric, a guide plate for the fabric, a depressing device for the 60 warp strands, movable to and from and

also having depressing action upon the guide plate, hook-shaped elevating devices for the weft strands, independent of and operating through the guide plate, pivotal supports for said hook devices, and means for simultaneously operating the depressing device and for rocking the hook devices.

7. In machines for inserting diagonal strands in woven cane fabric, a spring-supported guide plate, having a series of pins 75 extending from its upper face, adapted to enter the meshes of the fabric, said pins being in rows and the pins of one row staggered with relation to the pins of the other row, a needle adapted to slide on the guide 80 plate between the said pins, a device for operating the said needle, a depressing device movable to and from the guide plate and adapted for depressing action thereon and for engagement with the warp strands of 85 the fabric, and elevating devices located below the guide plate and operated therethrough, diagonally-opposite pins thereon, and means for operating the depressing and the elevating devices.

8. In machines for inserting diagonal strands in woven cane fabric, a tension-controlled guide plate for the fabric, depressing fingers arranged for concerted movement to and from the guide plate and for 95 depressing action thereon, said fingers being adapted for engagement with the warp strands of the fabric, pivoted hook-shaped elevating devices located below the guide plate and adapted for passage transversely 100 through the guide plate when said plate is depressed, connections between all the elevating devices, and means for imparting vertical movement to the depressing device and rocking movement to the elevating devices. 105

9. In a machine for inserting diagonal strands in woven cane fabric, a support, a guide for the cane fabric, springs intervening between said support and said guide, acting as bearings for the guide, pins located 110 upon the outer face of said guide, which pins are in rows, the pins of one row being opposite the spaces between the pins of the opposing row, said rows of pins serving as a race for a needle to carry the diagonal 115 strand, said pins being adapted to enter the meshes of the woven cane fabric, means for depressing said guide, and elevating devices for the fabric, located on said support and extending when the guide is depressed into 120 openings formed transversely in said guide between diagonally opposing pins.

10. In a machine for inserting diagonal strands in woven cane fabric, a support, a transversely arched guide for the fabric, located above the said support, springs engaging with opposing faces of the support and the said guide, said guide being provided with rows of pins forming a needle race, the pins of the rows being diagonally opposite 125 130

each other, said plate being likewise provided with transverse openings between diagonally opposing pins of the rows, elevating devices located below said guide, 5 which elevating devices consist of hook-shaped members fulcrumed upon the said support, the hook ends of the members entering the slots in the guide, and means for simultaneously rocking the said hook members, when the depressing device is raised and lowered.

11. In a machine for inserting diagonal strands in woven cane fabric, the combination with a bed, a support therefor, a treadle 15 carried by the support, a spring controlled beam having sliding movement in said support, connections between the beam and the said treadle, guides located on the said bed, arms extending through said guides and attached to the said beam, and a depressing device for the warp strands of the fabric, which depressing device consists of a bar carried by said arms and fingers extending down from said bar, of a spring-controlled 20 guide plate located below said depressing device, the guide plate being adapted to receive the woven fabric and being provided with a series of pins to enter the meshes of the fabric and with slots between the pins, 25 said depressing device in its downward movement being adapted to engage with said guide plate and force the same downward, and elevating devices consisting of a series of hook-shaped members pivoted to a fixed 30 support below said guide plate, the hook portions of which members extend into the openings in the guide plate, devices for rocking the said hook members, and means carried by said depressing device for operating 35 the said rocking mechanism and timing the operation thereof.

12. In a machine for inserting diagonal strands in woven cane fabric, the combination with a bed, a support therefor, a treadle

carried by the support, a spring controlled 45 beam having sliding movement in said support, connections between the beam and said treadle, guides located on said bed, arms extending through said guides and attached to said beam, and a depressing device for 50 the warp strands of the fabric, which depressing device consists of a bar carried by said arms and fingers extending down from said bar, of a spring-controlled guide plate located below said depressing device, said 55 guide plate being adapted to receive the woven fabric, being provided with a series of pins to enter the meshes of the fabric and with slots between said pins, said depressing device in its downward movement being 60 adapted to engage with said guide plate and force the same downward, and elevating devices consisting of a series of hook-shaped members pivoted to the fixed support below said guide-plate, the hook portions of which 65 members extend into the openings in the guide plate, devices for rocking said hook members and means carried by the depressing device for operating said rocking mechanism and timing the operation thereof, a 70 rocker arm extending through the bed, a needle adapted to carry a diagonal strand having its pointed end resting upon the guide plate and its outer end having crank connection with the rocker arm, pulleys located at opposite ends of the bed, a belt connected with the rocker arm and passed over said pulleys, a pinion carried by the shaft of one pulley, and a slide mounted upon the bed, having a rack member for engagement 75 with said pinion.

In testimony whereof I have signed my name to this specification in the presence of two subscribing witnesses.

MARTIN B. ZIMMERMAN.
